UNITED STATES PATENT OFFICE

MAX C. SHERMAN AND LEIGH P. HOFF, OF PHILADELPHIA, PENNSYLVANIA, ASSIGNEES TO FRANK H. DUNBAR, OF CLEVELAND, OHIO

LINING BORDER

Application filed February 25, 1926. Serial No. 90,471.

The invention relates to refractory linings, such as are used in boiler furnaces, and more particularly to the construction of the parts of said linings at and around openings such as those through which the solid residues of combustion are discharged.

Due to the intense heat furnace bottoms, hoppers and the like are usually lined with a refractory material, such as fire brick, extending substantially to the edges of the openings through which the ashes and other refuse are discharged. Around these openings the lining has been supported in various ways, such as for instance by cast-iron adapter frames.

Hoppers of prior types, particularly when exposed to the high temperatures incident to the use of finely divided fuels, presented many difficulties and disadvantages as, for instance, molten slag would accumulate and harden on the door closing the ash discharge opening, rendering the opening of the door difficult and sometimes impossible. The adapter frames would crack under the high temperatures and would become burned and require expensive repairs and replacements both to themselves and to the lining.

It is an object of the present invention to overcome difficulties experienced in prior types of ash hoppers.

Other objects will hereinafter appear.

The invention contemplates a border for openings through walls lined with refractory material which may be maintained at a lower temperature than the lining. This prolongs the useful life of the lining border and provides a cooling zone about the opening. Upon this zone molten slag running down the wall will be congealed and thus prevented from reaching the closure covering the opening.

One practical embodiment of the invention is illustrated in the accompanying drawings, in which—

Figure 1 is a perspective view of an ash hopper with parts broken away, and

Figure 2 is a fragmentary sectional perspective similar to part of Figure 1 but showing a modified form of hopper wall.

The hopper shown in Figure 1 comprises downwardly converging walls which termi-

nate about the ash discharge opening. The walls are lined with a refractory material such as fire brick 1, the lining being supported upon a metallic frame work indicated generally at 2. The ash discharge opening is surrounded by a gate-frame 3 and the opening of this frame is closed by a door or gate 4 which is carried by rollers supported by the bearings 5 mounted on beams 6.

The parts thus far described may be of any well known or desired construction.

Surrounding the ash discharge opening is a lining border 7, which consists of a plurality of separate blocks 8 of cast iron or any desired material. These blocks are supported upon the gate-frame 3 and the metal framework indicated generally at 2. The blocks each consist of a straight intermediate portion 9 normal to the surface of the hopper wall and which serves as an abutment to support the refractory lining. At the lower end of this wall is another wall 10 substantially perpendicular thereto and arranged to underlie the hopper lining as shown and at the other end is another substantially perpendicular wall 11 oppositely disposed and downwardly curved at its end to terminate in a bifurcated edge 12 which embraces a flange on the frame 3. The frame may be provided with apertures 13 to facilitate the circulation of air to the interior of the blocks.

It will be seen that the hollow of the block is exposed to the outside air, and that the walls are relatively thin. This permits the circulation of the air around the outside of the block to maintain the same at a much lower temperature than the lining of the hopper. The block therefore lasts much longer than would be the case if it were raised to the extreme temperatures produced within the hopper. Moreover, molten slag running down the hopper walls is chilled when it reaches the block border and is solidified before reaching the hopper door, thus preventing accumulations of slag hardening upon the door which would interfere with its operation. Due to the sectional construction of the border, the blocks may be readily replaced, if they become damaged in use, without necessitating the removal of more of the

lining than that overlying the upwardly extending flanges 10 of the blocks to be replaced. The removal and replacement of the blocks is also greatly facilitated as these blocks simply rest upon the frame 3 and the lower part of supporting framework 2, as clearly indicated in the drawings, so that when the refractory lining overlying flange 10 of the block has been removed, the block 10 need only be lifted out of place and another block may be readily set in place. Due to the low temperature maintained in the lining border and the fact that the same is sectional, the destructive strains set up in integrally cast linings, as used in prior hoppers, are avoided and cracking of the lining border is eliminated.

The stresses as produced in the lining border are also much smaller on account of the 20 relative thinness of the blocks which prevents any great inequality of temperature therein.

The hollows under the blocks may be associated with any ventilating or cooling system used on the exterior of the hopper to produce a continuous current of cooling fluid therethrough, and thus further reduce the operating temperature of the blocks.

In Figure 2 a ventilating or cooling system 30 is illustrated as comprising passages formed by framework 2 and an outer plating or sheathing 14 carried thereby, the heated air within the passages thus formed rising and inducing the cooling draught. Air may enter the cooling passages through the space between the lower end of plating 14 and the top flange of beam 6 or through apertures 13 in the gate frame. This air, of course, passes in contact with the blocks and maintains them at a low temperature.

While I have particularly described one embodiment of my invention, it will be obvious that the form of lining border may be materially changed, without departing from 45 the spirit of the invention, and also the lining border embodying my invention may be used for other openings than those of ash hoppers, being useful for any wall exposed to intense heat and I, therefore, do not limit 50 myself to the precise embodiment shown but claim as my invention all variations, modifications thereof coming within the scope of the said subjoined claims.

What is claimed is:

55 1. A furnace bottom having a refractory lining and provided with an opening therethrough, and recessed metal blocks engaging the lining and surrounding the opening, the recess opening outwardly of the furnace bottom.

2. A furnace bottom having a refractory lining and provided with an opening therethrough, and a border for the lining surrounding the opening and consisting of a 65 plurality of metal blocks, each having a re-

cess open to the outside air and the ends of the recesses of each section communicating with the recesses of adjacent sections.

3. A furnace bottom comprising a supporting framework including a gate-frame, a refractory lining carried by the supporting framework, and a metallic border carried by the framework and resting upon the gate-frame, the lining border consisting of a plurality of separate metal blocks.

4. A furnace bottom having a refractory lining and provided with an opening therethrough, a border for the lining surrounding the opening comprising a plurality of blocks, each having a recess open to the outside of the furnace bottom and communicating with the recesses in adjoining blocks, and a flange engaging with the refractory lining.

5. A furnace bottom having a refractory lining and provided with an opening therethrough, and a border for the lining surrounding the opening and consisting of a plurality of substantially Z-shaped blocks, one wall portion of which supports the refractory lining and another wall portion of which is open to the outside of the furnace.

6. A furnace bottom having a refractory lining and provided with an opening, a metal framework including a gate-frame defining the opening, and a border for said refractory lining surrounding said opening and supported by said gate-frame, the border consisting of a plurality of cast-iron blocks each provided with a ventilating passage on its exterior.

7. A furnace bottom comprising a supporting frame and a refractory lining, the frame being provided with passages through which a cooling current of air is conducted, the refractory lining being provided with a border composed of a plurality of separate metal blocks having recesses for cooling air in its exterior surface, the ends of the said passages opening into said recesses whereby currents induced in the passages cause cooling currents in said recesses.

8. A furnace bottom having a refractory lining and provided with an opening, a metallic framework including a gate frame surrounding the opening, a border for the lining supported by the gate-frame and composed of a plurality of separate blocks, each block being substantially Z shaped in cross-section and one flange of the Z lying between the gate-frame and the refractory lining and constituting a support therefor.

In testimony whereof we hereunto affix our signatures.

MAX C. SHERMAN.
LEIGH P. HOFF.

CERTIFICATE OF CORRECTION.

Patent No. 1,754,775.

Granted April 15, 1930, to

MAX C. SHERMAN ET AL.

It is hereby certified that the above numbered patent was erroneously issued to "Frank H. Dunbar, of Cleveland, Ohio", whereas said patent should have been issued to "The Allen-Sherman-Hoff Company, of Philadelphia, Pennsylvania, a Corporation of Pennsylvania, said corporation being assignee by mesne assignments of the entire interest in said invention; and that the said Letters Patent should be read with this correction therein that the same may conform to the record of the case in the Patent Office.

Signed and sealed this 24th day of June, A. D. 1930.

(Seal)

**M. J. Moore,
Acting Commissioner of Patents.**
